UNITED STATES PATENT OFFICE.

LOUIS WOJIDKOW, OF BROOKLYN, NEW YORK.

DESIGN FOR A STAND FOR CHAFING-DISHES.

SPECIFICATION forming part of Design No. 25,473, dated May 12, 1896.

Application filed April 11, 1896. Serial No. 587,218. Term of patent 3½ years.

To all whom it may concern:

Be it known that I, LOUIS WOJIDKOW, a citizen of the United States, residing at Brooklyn, in the county of Kings and State of New York, 5 have invented and produced a new and original Design for a Stand for Chafing-Dishes, of which the following is a specification, reference being had to the accompanying drawing, which shows a perspective view of the same.

10 The leading feature of my design consists in an upper larger ring and a lower smaller ring supported by legs formed of compound-curved curves, having their upper ends formed of an open-work scroll and decreasing 15 in width toward their lower ends or feet.

A is the upper larger ring, and B the lower ring, supported on legs O, each of which is formed at the top into a broadened open-work scroll C, from which the leg depends in a compound curve and decreasing in width toward the foot D. From each leg extends a bracket to the lower ring, said bracket consisting of the two arms E F, curved as shown.

What I claim is—

The design for a stand for chafing-dishes 25 substantially as herein shown and described.

LOUIS WOJIDKOW.
